By John Vaughan,
his ATTORNEY.

UNITED STATES PATENT OFFICE.

WILLIAM A. WILSON, OF ARLINGTON, NEBRASKA.

STOVEPIPE-HANGER.

No. 873,198.

Specification of Letters Patent.

Patented Dec. 10, 1907.

Application filed July 1, 1907. Serial No. 381,781.

To all whom it may concern:

Be it known that I, WILLIAM A. WILSON, a citizen of the United States of America, residing at Arlington, in the county of Washington and State of Nebraska, have invented 5 a new and useful Stovepipe-Hanger, of which the following is a specification.

My invention relates to improvements in hangers having a separable rod connecting a 10 pipe-clasp with a wall or ceiling attaching part; and the objects of my improvement are, first, to facilitate fastening the hanger to a wall or ceiling without the use of other tools; second, to provide a hanger universally jointed at both ends, so that it can be 15 set at any angle either to the pipe or to the surface to which it is fastened; third, to provide an elastically gripping metallic clasp to adjustably and detachably engage the pipe; fourth, to contrive means whereby the 20 hanger-rod can be adjusted to any length; and fifth to facilitate the use of stock materials in the construction, at the same time producing a light, ornamental and substantial hanger. I attain these objects by the 25 mechanism illustrated in the accompanying drawing, in which—

Figure 1 is a perspective view of such a hanger suspended vertically from a ceiling 30 as in use; Fig. 2 is an elevation illustrating the construction and connection of the self-adjusting elastically-gripping pipe-clasp; Fig. 3 is a perspective view illustrating the use and connection of the top part of the rod 35 with the ceiling or wall attachment; and, Fig. 4 illustrates the intermediate coupling of the two parts of the hanger-rod.

Similar numerals refer to similar parts throughout the several views.

40 The rod connecting the pipe-clasp 8 and the wall or ceiling fastening, is made in two parts 3 and 7, detachably fastened together by the turnbuckle or coupling nut 5. The part 3 has one end 4 threaded to enter the 45 coupling nut and a short portion of its opposite end bent at a right angle and terminated with a head 3'. This rod is inserted through the screw-eye 2 as shown in Fig. 3; in which position it serves as a lever to turn the screw-eye and drive its threaded part 2' into the 50 ceiling 11 through the finishing-plate or collar 12; it is then passed on through until the bent portion adjacent to the head 3' is seated in the screw-eye, as shown in Fig. 1, thereby 55 forming a hinged connection which, with the

turning of the screw-eye, gives this end of the rod universal angular adjustment from its point of attachment. Part 7 is made like part 3 and is interchangeable therewith, having the head 7' at its bent end and the single 60 difference that its threaded portion 6 is longer so that a part may be broken or cut off for small adjustments of length,—different lengths of rods being resorted to for greater adjustment.

65 The pipe-clasp 8 is made of a single strip of sheet metal, the middle portion bent flatwise to encircle the pipe; the end portions then bent first outward and then inward to form the elliptical shaped loops 10 and 10'; the ends 70 9 and 9' further bent until they are closed flat against the inside of the pipe encircling portion 8. These loops 10 and 10' are cross-perforated to form attaching-ears so that the rod 7 can be inserted through across the 75 loops, as shown in Fig. 2, after the clasp is placed around the pipe. The rod 7 is drawn on through and the loop-attaching-ears 10 and 10', forced onto the short angled part of the rod adjacent to the head 7' and the rod 80 swung up to the position shown in Fig. 1; this compresses and flattens the loop-ears as shown in Fig. 1, and draws the clasp around the pipe with an elastic grip, so that it retains its position until released by swinging 85 the rod back and thus releasing the grip on the pipe to shift the position of the clasp or to remove it therefrom. The inwardly lapped ends 9 and 9' reinforces the bases of the loop-ears giving them requisite strength 90 to allow the use of very thin sheet metal in the clasp which fits closely and neatly to the pipe. That part of the rod seated through the loop-ears turns therein to allow the hanger to swing to any angle in a plane 95 agreeing with the line of pipe, and by shifting the clasp around the pipe any lateral angle thereto may be attained. After the parts 3 and 7 are attached the threaded coupling, as shown in Fig. 4, is run clear onto the threaded end 4, the end 6 brought into position and the coupling turned down a part of its length 100 onto the threaded end 6, coupling the two parts together as shown in Fig. 1.

105 This hanger having its attaching ends both universally hinged is adapted to hanging pipe at any angle and supporting it from surface planes at any angle thereto; it may be used in pairs set at different angles for very rigid support; and adding to this, its length adjust- 110

ment, it is adapted to meet all the conditions of hanging stove-pipe and renders the pipe easily taken down for cleaning or removal.

I claim:

- 5 1. A pipe-hanger comprising, a pipe-clasp made of a single sheet-metal strip bent centrally to embrace the pipe and having outwardly looped bends to form abutting spring ends to said central bend and said looped 10 bends cross-perforated to form attaching ears, a two-part separably-coupled hanger-rod having one end bent adapted to hinge in an attaching screw-eye and the opposite end headed and bent adapted to be disposed 15 through said attaching ears to hinge the rod therein and draw said spring-ends together.
2. A pipe-hanger comprising, an open encircling pipe-clasp with ears at its ends, an

attaching screw-eye, a two-part separably-coupled hanger-rod one part adapted to slide 20 through and bent to hinge in said screw-eye and the other part bent to adapt it to be separably connected through said ears to hinge therein and draw said ears together.

3. A pipe-clasp for pipe-hangers consisting 25 of, a single piece of sheet metal having a central bend to embrace the pipe, adjacent portions bent outward in elliptical shaped loops to form spring connecting ears at the ends of the clasp and the ends of the metal strip each 30 bent and disposed against the inside of the central bend at the base of its adjoining ear.

WILLIAM A. WILSON.
